BOWSTRING DRAWING AND RELEASING DEVICE

Dale F. Halter, 25825 Brynmawr Ave.,
Hayward, Calif. 94544

Filed Mar. 22, 1971, Ser. No. 127,060

Term of patent 14 years

Int. Cl. D22—99
U.S. Cl. D22—99

FIG. 1 is a perspective view of a bowstring drawing and releasing device showing my new design, the string and arrow being shown in broken lines for illustrative purposes only;

FIG. 2 is a plan view thereof;

FIG. 3 is a side elevational view thereof;

FIG. 4 is an end elevational view as seen from the top of FIG. 2;

FIG. 5 is an elevational view of the side opposite that shown in FIG. 3;

FIG. 6 is an end elevational view as seen from the bottom of FIG. 2.

I claim:

The ornamental design for a bowstring drawing and releasing device, as shown and described.
